(57) **CLAIM**

The ornamental design for a water diverter, as shown and described.

DESCRIPTION

FIG. 1 is a top, front, right side perspective view of the water diverter of the present invention;

FIG. 2 is a front elevational view of the water diverter of FIG. 1, the rear view being a mirror image thereof;

FIG. 3 is a cross-section view of FIG. 1 taken along line 3—3;

FIG. 4 is a left side elevational view of the water diverter of FIG. 1, the right view being a mirror image thereof;

FIG. 5 is a top plan view of the water diverter of FIG. 1; and, FIG. 6 is a bottom plan view of the water diverter of FIG. 1.
